E. BOWMAN

CHIROPRACTIC TABLE

Filed March 28, 1922

Fig. 3.

Inventor

Elva Bowman

By

H. G. Burns Attorney

UNITED STATES PATENT OFFICE.

ELVA BOWMAN, OF FORT WAYNE, INDIANA.

CHIROPRACTIC TABLE.

Application filed March 28, 1922. Serial No. 547,436.

To all whom it may concern:

Be it known that I, ELVA BOWMAN, a subject of the King of Great Britain, and resident of Fort Wayne, in the county of Allen and State of Indiana, have invented certain new and useful Improvements in Chiropractic Tables, of which the following is a specification.

This invention relates to improvements in 10 chiropractic tables, especially the means for supporting the head, sternum and abdomen, and the object thereof is to provide a face rest that may be adjustably tilted longitudinally and also adjustably raised and 15 lowered relative to the sternum support.

Another object is to provide a flexible shield for the gap between the sternum and abdominal supports which will not interfere with the relative movements thereof so as 20 to prevent portions of the patient's body from becoming wedged therebetween.

And a further object is to provide means for the support of the hands of the patient so arranged that the patient's arms will be 25 extended in a state of relaxation.

The above objects are accomplished by the construction illustrated in the accompanying drawings in which:—

Fig. 1 is a side elevation of the head 30 pedestal of a table having embodied therein the present invention, parts being shown in central section;

Fig. 2 is a front end elevation projected from Fig. 1; and

Fig. 3 is a plan view of the same, a portion 35 of the shield being broken away.

The characters appearing in the description refer to parts shown in the drawings and designated thereon by corresponding 40 characters.

The invention consists of a head frame 1 in which is hinged a swinging shelf 2 having upon its rear end an abdominal support 3. The construction of the abdominal 45 support and the mechanism 4 that sustains its shelf is similar to the construction shown in my previous application for improvements in chiropractic tables, Serial Number 479,751, filed June 23, 1921. However, the 50 particular manner of yieldingly sustaining the abdominal support in normal position is immaterial to the present invention as other mechanism may be substituted which would be capable of properly sustaining the 55 shelf.

Upon the upper end of the frame 1, at the rear thereof is a cross piece 5 to which is hinged a pair of sternum rests 6 which are spaced apart and which are normally sustained in position by corresponding studs 60 that project upwardly from the shelf 2.

A flexible shield 8 is secured along its forward edge to the forward edges of the sternum rests and extends over the sternum and abdominal rests and is suspended across 65 the gap therebetween. The shield has a slot 9 in its forward middle portion exposing the space between the sternum rests which is intended to afford freedom for the throat of the patient. The rear portion of the 70 shield lies loosely over the abdominal rest and serves to sustain the breasts of the patient at the gap between the sternum and abdominal supports.

A movable frame 10 is supported above 75 the frame 1, at its front end upon a vertically adjustable prop 11 and at its rear portion upon a pair of swinging brackets 12. The rear end of each bracket is pivoted in the frame 1, and the front ends of the 80 brackets are connected by a cross rod 13 that extends through a bifurcated block 14 which is adjustably positioned in a vertical slot 15 in the prop 11, there being a thumbscrew 16 in connection with the block for 85 holding it in adjusted positions. Each bracket 12 has an upwardly extending arm 17 that has pivotal supporting connection with the frame 10. The prop 11 has adjustable supporting connection at its lower end 90 in the frame 1, there being a cleat 18 on the prop for engaging cleats 19 in the frame so that the prop is sustained in its various positions.

The movable frame 10 has fixed at each 95 end thereof an angle iron 20 which loosely engages in the corresponding ends of a pair of transversely slidable plates 21, and upon each of said plates is hinged a face rest 22 which is longitudinally disposed. 100 Also, upon the frame 10 is secured a block 23 in the center thereof and extending up to the plane of the plates 21. The face rests, when moved to central position by shifting the plates 21, extend over the block 105 23 which prevents the rests from being tilted when in that position.

Upon each side of the frame 1 is secured a horizontal hand-rail 24, the forward end of which is looped outwardly so that its in- 110

turned terminal 25 will accommodate the full width of the hand and form a rest therefor.

In using the invention the movable frame 5 is adjustably raised or lowered and the face rests are parted and tilted accommodately to the head of the patient, the frame being adjusted by manipulating the prop 11 and by vertically adjusting the block 14 on the 10 prop so that the rear end of the frame is thereby vertically adjusted independently of its forward end.

When the patient is being given an adjustment the abdominal support becomes 15 pressed and the sternum rests become tilted, and the flexible shield sustains the breasts of the patient above the gap between the sternum rests and the abdominal support, thus avoiding injury of the members.

20 The elongated hand-rails permit the patient to support himself while assuming the customary posture upon the table, after which, by sliding the hands forwardly along the rails to the looped ends, the arms there- 25 by become fully extended which invites relaxation and induces the patient to lie prone upon the apparatus.

What I claim is:—

1. In a chiropractic table, a frame; a vertically movable yieldingly sustained abdominal support; a pair of sternum rests spaced apart on the frame adjacent the abdominal support; a flexible shield secured to the sternum rests and extending loosely 35 over the abdominal support; a vertically adjustable prop at the front of the frame; a block vertically adjustable on the prop; a pair of brackets pivotally supported at the rear of the frame and having sustained relation with said block; and a head supporting means sustained at its forward end upon the prop and at its rear portion upon said brackets.

2. In a chiropractic table, a frame; a vertically adjustable prop at the front of the frame; an adjusting member movable on the prop; a swinging member pivotally supported on the frame at the rear end and having supported relation at its forward

end with said adjusting member; and a head 50 supporting member sustained at one end by the prop and at its opposite end upon the swinging member.

3. In a chiropractic table, a head supporting member; a vertically adjustable prop 55 sustaining the front end of said member; and a swinging member sustaining the rear end of the former member and adjustable connection with the prop.

4. In a chiropractic table, a frame; a head 60 supporting member; a vertically adjustable prop sustaining one end of the member; and means adjustably connected with the prop and pivotally connected in the frame and having supporting relation with the opposite 65 end of the head supporting member.

5. In a chiropractic table, a frame; a pair 70 of plates longitudinally disposed and laterally adjustable in the frame; a pair of face rests hinged respectively on the corresponding plates and being adapted to be tilted inwardly when the plates are moved outwardly; and a block on the frame adapted to engage and sustain the face rests in horizontal position when the plates are moved 75 inwardly.

6. In a chiropractic table, a frame; a pair 80 of parallel face rests longitudinally disposed; a pair of corresponding sternum rests adjacent the rear ends of the face rests, said sternum rests being spaced apart; a yieldingly sustained abdominal support adjacent said sternum rests; and a flexible shield extending over the sternum rests and abdominal support and having a slot in its forward 85 portion between the sternum rests.

7. In a chiropractic table, a longitudinally disposed hand rail extending along each side of the table at the head portion thereof and having a looped portion at the front end 90 thereof forming a hand hold.

In testimony whereof I affix my signature in presence of two witnesses.

ELVA BOWMAN.
